UNITED STATES PATENT OFFICE.

DAVIS WEINSTOCK, OF NEW YORK, N. Y.

DESIGN FOR A DISPLAY-CASE.

41,370.

Specification for Design.

Patented May 9, 1911.

Application filed February 20, 1911. Serial No. 609,845. Term of patent 7 years.

To all whom it may concern:

Be it known that I, DAVIS WEINSTOCK, a citizen of the United States, residing in New York city, borough of Manhattan, county and State of New York, have invented a new, original, and ornamental Design for Display-Cases, of which the following is a specification, reference being had to the accompanying drawings, forming part thereof.

The figure is a perspective view of a display case, showing my new design.

I claim:

The ornamental design for a display case, as shown.

DAVIS WEINSTOCK.

Witnesses:

HERMAN HERST, Jr.,
T. F. BOURNE.
